GLARE FREE LIGHTING DEVICE

Alvin M. Marks, Flushing, N. Y.

Application June 15, 1946, Serial No. 676,916

7 Claims. (Cl. 88—65)

1

This invention relates to devices for providing glare-free illumination.

An object of this invention is to provide a lighting device which gives glare-free illumination to both horizontal and vertical surfaces.

The novel features characteristic of this invention are set forth with particularity in the appended claims. The invention itself, however, both as to its organization and its method of operation, together with additional objects and advantages thereof, will best be understood from the following description of a specific embodiment when read in connection with the accompanying drawing, in which:

Figure 1 shows a means for providing glare-free illumination in the form of selectively polarized light adapted to illuminate both horizontal and vertical surfaces from a single source.

Figure 2 shows a diagrammatic showing of a system of general room illumination adapted to provide low intensity light and glare-free illumination of vertical and horizontal surfaces simultaneously.

In Figure 1 I show a particular means for providing polarized illumination in all radial directions from a central source so as to provide simultaneous glare-free illumination for objects having both vertical and horizontal surfaces. To effect this result, it is necessary that light directed onto the vertical and horizontal surfaces be respectively polarized in different planes in its path from the source of illumination. By way of illustrating the vertical surfaces which are to be illuminated, I show a picture 150 and a ray 151 polarized in a vertical plane as indicated at 152 impinging upon that picture to provide a glare-free illumination. I also show a horizontal surface such as a table or a floor 153 and a ceiling 154 and rays 155 and 156 respectively impinging on these respective surfaces, said rays 155 and 156 being polarized in a plane which is normal to their plane of incidence as shown by the dots 157—158 respectively.

To provide this dual glare-free illumination by means of properly positioned polarized media cooperating with directed beams of light, I have shown by way of illustration, a fixture in which I provide a light source 160 surrounded by a sheet polarizer containing aligned herapathite crystals or other suitable polarizers. The rays which impinge upon the horizontal surface 153 first pass through a circumferential polarizer. It comprises segmented radial portions 162 with the axis of polarization 163 lying in the indicated planes. The axis of polarization of these seg-

2

ments coincide with the tangent of the circle whose center is the common vertical axis passing through the light source. By means of these radial segments of polarized sheets, light passing downwardly from light source 160 is plane polarized to provide the properly polarized light beam 155 as described above.

In place of the segmented circular sheet a sheet which has the crystals thereof aligned in concentric circles may be employed. Such a sheet may be made, for example, by the method disclosed in the patent to Zocher, No. 1,873,951 by applying a dichroic dye to the surface of a transparent support and rubbing the surface in a rotating direction. Such a polarizer may also be produced by polishing a sheet of polyvinyl alcohol containing a dichroic dye in a circular direction or by other ways known in the art.

Another means of polarizing rays which are directed upon horizontal surfaces is shown as a frustum of a cone 165 which may be a completed cone as shown by the dotted lines 166 or may terminate in a cut-off section 167 as shown in dotted lines. The cut-off section 167 may comprise an absorbing surface or an internal reflecting surface of suitable characteristic or may be left open for the passage of non-polarized illumination as here shown. The frustum of the cone 165 may be constructed of any suitable polarizer such as a plastic sheet polarizer containing properly aligned crystals. The axis of polarization of the frustum of the cone is shown by dotted line 168 and said axis of polarization follows the circumference of concentric circles having a center in the common vertical axis of the cone. Light then passing from the light source through this cone comprising the polarized sheet is properly polarized as shown at 158 for the light beam 156. It is understood that the frustum of the cone or the completed cone shown may also be applied in lieu of the circumferential polarizer 162 to the lower horizontal surface. In other words, I provide the cone or cone frustum shape having a polarizing axis as indicated, as an important, independent aspect of my invention to provide proper polarization for light to be directed upon horizontal surfaces.

For light which is to be simultaneously directed onto vertical surfaces such as picture 150, I provide a cylinder which may comprise a sheet polarizer or segmented flat strips. It is important that the axes of polarization be as indicated by the dotted lines 170 for illuminating vertical surfaces. In this case, the axes of polarization of the polarizing cylinder is such that these axes are all

parallel to the common vertical axis. The effect of this construction is to polarize horizontally-directed rays 151 in a vertical plane as shown at 152 and furthermore provide glare-free illumination for such vertical surfaces. These horizontally-directed rays are such that they are substantially parallel to horizontal surfaces 153—154 and so cannot be reflected from these horizontal surfaces to cause a glare. It is understood that rays 151 are also directed upon vertical surfaces at approximately 33° so as to provide the proper angle of incidence for best glare-free illumination.

To effect this proper angular direction, it is best to provide block-outs or louvres and prevent a direct 90° angular impingement of the polarized light onto the vertical surface. Areas which are not illuminated because of these block-outs can be properly illuminated with glare-free polarized lamps suitably spaced apart which are positioned to direct, at the proper angle, polarized light therefrom. The figure is diagrammatic and is reduced to essentials, but it is understood that the principles embodied therein can be improved or enhanced by additions of suitable reflectors, diffusing mediums and all other well known devices common in the art.

In Figure 2 I show a system for providing glare-free low intensity light for a room and its contents which, of course, comprise both horizontal and vertical surfaces. To do this, I provide simultaneously horizontally directed light rays containing vertically plane polarized light and light directed upon horizontal surfaces containing light polarized in a plane normal to its plane of incidence, both such families of rays being simultaneously projected. To carry out this system of illumination, I provide a light source 175 which simultaneously projects light rays 176, 177 and 178 through polarizers 174 and 180. Polarizer 174 has an axis of polarization adapted to polarize light beam 176 so as to provide light vibrating in a plane normal to the plane of final incidence of light as shown at 181. This so-polarized light is directed onto a suitable reflecting surface 182.

Surface 182 has a suitable reflecting surface such as a metallic reflecting surface. For example, 182 might be a wall of suitable curvature covered with aluminum particles in a transparent vehicle or the wall might comprise a metallic foil paper which might contain embossed designs for the purpose of ornamentation. In the event that the general plane of the wall is desired to be substantially vertical, it is contemplated that the wall paper be suitably embossed or molded with directional metallic planes to cooperate with the aforementioned light source so as to direct a polarized beam upon horizontal surfaces at the angles indicated in this figure. Specifically I mean by this that I may provide angular directing reflecting surfaces comprising a multiplicity of suitably oriented facets obtained by molding or embossing which, although collectively positioned in a substantially vertical plane, effectively act to direct light therefrom in the angular range which would normally be obtained by a plane surface having the curvature indicated at 183.

Referring now to the path of the light ray 176 after reflection from the reflecting surface 182, this polarized light is directed downwardly upon horizontal surfaces at the best angle to provide glare-free illumination. This range is, for example, from 20° to 70° with a preferred angle of approximately 33°. Now referring to the rays intended for the illumination of vertical surfaces,

specifically 177 and 178, I provide for the polarization of these rays by polarizer 180 which polarizes said rays in a vertical plane as indicated at 185 and 186. Rays 177 and 178 are impinged upon the wall reflecting surface 183 which is of the character previously discussed and which is such that the particular curved section or embossed section cooperating with the directed rays 177 and 178 produce horizontally reflected rays 187 and 188.

In the drawing it is understood that rays 187, 188 and 189 are all traveling in horizontal directions; any appearance to the contrary being due to the perspective of the drawing. By horizontal directions is meant that the rays travel in a substantially horizontal direction, but of course there will be some deviation therefrom due to scattering and diffusing effect on the reflecting surface 183. A bottle 190 is shown as illustrative of an object having vertical surfaces.

It is to be pointed out further that vertical rays 187, 188 and 189 are preferably constrained by properly directing the reflecting surfaces or by blocking members so that said rays impinge upon said vertical surfaces at substantially the proper angle therewith.

By the provision of a wall surface which imparts the indicated angular direction of the respective rays and which comprises a reflector that reflects polarized light, I provide not only for the aforementioned glare-free illumination of both vertical and horizontal surfaces, but I also provide a low intensity soft illumination within the room.

Particularly I have provided a new system of illumination which comprises the directing simultaneously of a multiplicity of light rays, polarizing these in suitable planes for the ultimate purpose of providing glare-free illumination for the particular surfaces which the light rays are to illuminate and for further carrying out this scheme I have provided metallized or other suitable non-depolarizing reflecting surfaces of large area which, for example, may be the walls or ceiling of the room and as a further modification of this system I provide an ornamentation of these surfaces, such ornamentation being such as to fully absorb the light in certain areas or to reflect it without depolarization.

It is to be noted that the polarizing means 174 and 180 comprise two polarizers having their axes of polarization at right angles and that these polarizers are respectively positioned so as to intercept and properly polarize light which after reflection from the cooperating reflecting surface is directed substantially onto particular planes.

The Figure 2 is intended to be illustrative of a broad new principle of great importance and utility and is not limiting in any way, as many constructions thereto of devices and methods well known in the art could be made, all without departing from the broad scope of this invention.

This application is a continuation-in-part of application Serial No. 240,608, filed November 16, 1938 (now Patent 2,402,176, June 18, 1946) which in turn is a continuation-in-part of application No. 755,557, filed December 1, 1934, now abandoned.

Although certain specific embodiments of this invention have been shown and described, it will be understood that many modifications thereof are possible. This invention, therefore, is not to be restricted except insofar as is necessitated by

the prior art and by the spirit of the appended claims.

I claim:

1. In a nonglare lighting device, of the type in which the lighting device is supported from a substantially flat surface which is to be illuminated, the novel combination which comprises a supporting member extending in a perpendicular direction with respect to said flat surface, a light source held by said supporting member and positioned on an axis normal to said flat surface and adapted to cast light in divergent directions, a polarizing disc also held by said supporting member and being parallel to said flat surface and centered on said normal axis, the polarizing disc comprising a plurality of segments, the polarizing axis of which are substantially normal to the radii from the center of said disc, whereby nonglare polarized illumination is obtained in a plurality of directions simultaneously.

2. The device of claim 1 in which the polarizing disc is composed of segments so combined that the planes of polarization of light transmitted through the disc is tangential with respect to circles centered on said normal axis, in planes parallel to the illuminated surface whereby radially directed nonglare polarized illumination is obtained in a plurality of directions simultaneously.

3. The device of claim 1 in which the segments of said polarizing disc are so numerous as to produce essentially circular lines of polarization.

4. In a nonglare lighting device of the type in which the lighting device is supported from a substantially horizontal flat surface which is to be illuminated, the novel combination which comprises, a light source positioned on a vertical axis adapted to cast light in substantially all directions, and in proximity thereto a compound polarizing screen comprising a segmented disc, each of said segments having a polarizing axis substantially perpendicular to the line bisecting the angle of the segment of the disc to polarize light tangentially with respect to circles in horizontal planes and centered on said vertical axis, said lighting device being placed so that the said disc is located between the light source and the said flat surface which is to be illuminated, said compound polarizing screen also comprising a portion surrounding the light source extending from the periphery of said disc, said surrounding portion having its plane of polarization in a vertical direction being adapted to polarize horizontally directed light from said light source in a vertical plane, whereby radially directed nonglare polarized illumination for both horizontal and vertical surfaces is obtained in a plurality of directions simultaneously.

5. In a nonglare lighting device of the type in which the lighting device is supported from a substantially horizontal flat surface which is to be illuminated, the novel combination which comprises, a light source positioned on a vertical axis adapted to cast light in substantially all directions, and in proximity thereto a compound polarizing screen comprising a segmented polarizing disc each of said segments having a polarizing axis substantially perpendicular to the line bisecting the angle of the segment of the disc to polarize light from said light source tangentially with respect to circles centered on said ver-

tical axis and in horizontal planes, said disc being located between the light source and the said flat surface which is to be illuminated, said compound polarizing screen also comprising a portion surrounding the light source extending from the periphery of said disc, said surrounding portion having its plane of polarization in a vertical direction being adapted to polarize horizontally directed light in a vertical plane, said compound polarizing screen further comprising a frustoconical portion the larger end of which is united to the end of said surrounding portion opposite to the disc, said frustoconical portion having polarizing elements oriented so that the transmitted light is plane polarized tangential to circles constructed on the frustoconical surface whereby radially directed nonglare polarized illumination is obtained in a plurality of directions, for horizontal and vertical surfaces, simultaneously.

6. In a nonglare lighting device, a light source adapted to cast light in substantially all directions in combination with a compound polarizing screen, said screen comprising a cylindrical portion surrounding the light source and having polarizing axes adapted so as to polarize horizontally directed light in a vertical plane and a frustoconical portion closing one end of the cylindrical portion, said light source being located on the axis of said frustoconical portion and said frustoconical portion being composed of a polarizing element so constructed that transmitted light is plane polarized tangential to circles constructed on the frustoconical surface.

7. In a nonglare lighting device, a source of light, an enclosure made of polarizing material surrounding said light source said polarizing enclosure comprising a dichroic polarizing member in the form of a frustoconical section, the polarizing axes extending substantially along circles, the planes of which circles are normal to the axis of the frustoconical section, said source of light being located in the axis and adjacent the larger end of said frustoconical section so that every ray passing through said frustoconical section will be polarized in a plane normal to the plane of incidence of the ray on the surface viewed whereby radially nonglare illumination is obtained in a plurality of directions simultaneously.
